UNITED STATES PATENT OFFICE.

STORM B. HAARBYE, OF CORAOPOLIS, PENNSYLVANIA, AND HOWARD G. McILVRIED, OF PITTSBURGH, PENNSYLVANIA, ASSIGNEES TO AMERICAN SHEET AND TIN PLATE COMPANY, OF PITTSBURGH, PENNSYLVANIA, A CORPORATION OF NEW JERSEY.

DOUBLING APPARATUS.

Application filed September 7, 1921. Serial No. 499,016.

To all whom it may concern:

Be it known that we, STORM B. HAARBYE and HOWARD G. McILVRIED, a subject of the King of Norway and a citizen of the United States, respectively, residents, respectively, of Coraopolis and Pittsburgh, both in the county of Allegheny and State of Pennsylvania, have invented certain new and useful Improvements in Doubling Apparatus, of which the following is a specification.

This invention relates to apparatus used in doubling metal sheets and plates and while not limited thereto, more particularly relates to apparatus used in matching and doubling sheets or plates at an intermediate point in the operation of rolling such sheets or plates in packs.

One object of our invention is the provision of an improved form of doubling apparatus wherewith the plates to be doubled are received at or about the floor level of the mill, are matched, and are then doubled and returned to the same level.

Another object of the invention is to provide an improved doubling mechanism having in combination therewith a novel matching apparatus for alining the plates side-wise and endwise, preparatory to being doubled.

A further object of the invention is to provide an improved doubling apparatus having the novel constructions, arrangements and combination of parts set forth in the following specification and illustrated in the accompanying drawings, in which—

Figure 1 is a front or end elevation of a doubling mechanism constructed in accordance with our invention.

Figure 2 is a sectional side elevation of the same, the section being taken on the line II—II of Figure 1.

Figure 3 is a top plan of the apparatus shown in Figures 1 and 2.

Referring now to the drawings, the numeral 2 designates a pit, below the floor level of the mill, in which the doubler and doubler operating mechanism is located and

3 is the base of the doubler secured on the bottom of the pit and supporting the side frames 4 of the doubler. 50

A doubling knife 5 is mounted to reciprocate vertically in guideways 6 formed in the upper end or head of the side frames 4, which extend above the level of the floor A. This knife 5 is adapted to be forced down 55 so as to enter the plate or pack of plates between or into the "bite" of a pair of rolls 7—7^a, these rolls, as is shown in the drawings, being journaled in the side frames 4 in an axially horizontal position and at such 60 elevation that the top faces thereof are approximately at the level of the mill floor A.

The plate or pack doubling knife 5 is adapted to be actuated by a pair of opposed single acting, fluid pressure cylinders 8 and 65 9, in which the opposite ends of the piston 10 are operatively mounted. Fluid under pressure is supplied to the cylinders 8 and 9 by pipes 8^a and 9^a respectively. The piston 10 is provided with an aperture at about the 70

middle of its length to receive the pin 11 which carries one end of the links 12 and 13 on its opposite ends. The links 12 and 13 are pivotally connected at the other end thereof to the lower ends of the arms 14 and 75 15 of the yoke or forked rocking lever 16, which is keyed or otherwise secured to the rocking shaft 17. The shaft 17, which is journaled in suitable bearings on the side frames 4, carries rocking levers 18 and 19 80

at its respective ends and these levers 18 and 19 are pivotally connected to the lower ends of lengthwise adjustable connecting rods 20 and 21. The upper ends of the connecting rods 20, 21 are pivotally connected so the 85 ends of the doubling knife 5, which project through the guideways 6 in the side frames 4.

By reference to the drawings, it will be seen that when fluid pressure is admitted 90 to the single acting cylinder 9, through the pipe 9^a the shaft 17 will be rocked in a clockwise direction and will thereby cause the levers 18 and 19 to move the knife 5

2
downwardly against a plate or series of matched plates positioned below this knife. It also will be seen that when fluid pressure is admitted to the cylinder 8, through pipe 5 8^a the shaft 17 will be rocked in a counter-clockwise direction, so as to move the levers 18 and 19 upwardly, thus forcing the connecting rods 20-21 to move upwardly and thereby retract or lift the knife 5 into its 10 starting position.

The doubling rolls 7 and 7^a are journaled in bearing blocks 23-24 mounted in the side frames 4, these bearing blocks being backed by helical springs 25, 26, which form 15 a yielding mounting that facilitates the entrance of a plate or pack of plates between said rolls.

The rolls 7 and 7^a are rotatably connected by the meshing gears 27 and 28 mounted on 20 one end of the rolls. A reversible driving motor 29 is connected to the roll 7^a through a train of reducing gearing consisting of a spur pinion 30 on the armature shaft of the motor 29, which is in mesh with a spur gear 25 31 on one end of the jack shaft 32, this shaft having a spur pinion 33 at its other end meshing with the spur gear 34 on the end 30 of the roll 7^a opposite that having the gear 27. It will be clearly seen that the motor 29, through the reducing gearing, will positively drive both of the rolls 7 and 7^a, since these rolls are rotatably connected by the spur gears 27, 28, in either of the opposite directions.

35 A plate or pack of plates, when passed between the rolls 7-7^a far enough to be doubled is automatically returned to the floor level by reversing the direction of rotation of the rolls 7-7^a. This is accomplished by means of the tripping finger or trigger 36, which is keyed or otherwise secured to the shaft 37, this shaft being journaled in bearings on the side frames 4. The shaft 37 has one end operatively connected 40 to a reversible limit switch 38 which controls the reversing driving motor 29. The plates in passing downwardly between the rolls 7-7^a strike the trigger 36 and rocks the 45 shaft 37 so as to operate the reversing switch 38, thus reversing the direction of rotation of the motor 29 and rolls 7-7^a and causing the doubled plate or pack to travel upwardly to the floor A.

50 When a series of plates is to be doubled, they are placed on the floor A below the knife 5, and as it is desirable to have all the plates in alignment or matched, a matching mechanism is provided to co-act with the 55 doubling apparatus.

The matching mechanism comprises tilting end fingers or stops 40-41 and two pairs of side fingers or stops 42 and 43. The end stops 40-41 of this matcher are pivotally 60 mounted on pins 44 and 45 secured to the

carriages 46 and 47 respectively, so as to tilt to allow the plates to slide into position on the doubling mechanism.

The carriages 46 and 47, which are slidably mounted in guides 48 and 49, so as to move toward and away from the plates, have lugs 50 and 51, which project downwardly through guides 48 and 49 and are connected to levers forming the carriage operating mechanism. The lug 50 on the carriage 46 75 is pivotally connected by a short link 52 to the upper end of a rocking lever 53, the rocking lever being keyed or otherwise secured at an intermediate point in its length to a rocking shaft 54, which is journaled on 80 the bearing bracket 55. A lever 56, which has one end keyed or otherwise secured to the shaft 54 is pivotally secured by the link 57 to the upper end of the piston rod 58 of a double acting fluid pressure cylinder 85 59. The lug 51 on the carriage 47 is pivotally connected by a short link 60 to the upper end of a lever 61, the lower end of this lever being pivotally mounted on the bracket support 62 and being pivotally connected intermediate its ends by the link 63 to the lower end of the lever 53. The levers 53 and 61 are held in their retracted or outermost position (that shown in Figure 2), by coil springs 64 and 65 respectively, one end 90 of these springs being secured to suitable anchors conveniently located in the side walls of the pit 2.

It will be readily apparent that when fluid pressure is admitted to the lower end 100 of the cylinder 59, the piston rod 58 will be moved upwardly and rock the lever 56, which in turn will rock the shaft 54 and lever 53, this movement of the lever 53 105 pulling the link 52 and carriage 46 with its stop finger 40 inwardly toward or against plates lying above the doubler rolls. Movement of the lever 53 also pulls on the link 63 and rock lever 61 and, through the link 60, moves the carriage 47 with its stop finger 41 inwardly against the end of the plates opposite that engaged by the finger 40.

The pairs of stops or fingers 42, 42 and 43, 43 also are mounted on carriages 66 and 67, respectively, which are slidably mounted 115 on guides 68 and 69 so as to move in a horizontal plane at right angles to the direction of movement of the stop fingers 40, 41.

The carriages 66 and 67 have downwardly 120 projecting ears or lugs 70 and 71, respectively, the lugs 70 on the carriage 66 being pivotally connected by short links 72 to the upper end of the rocking levers 73, which are pivotally mounted at a point adjacent to their lower ends on brackets 74. The 125 lower ends of the levers 73 are pivotally connected, by links 75, to the upper ends of the rocking levers 76, these levers being keyed or otherwise secured at the middle of the length thereof, to the rock shaft 77. A lever 130

78 having one end keyed or otherwise secured to the shaft 77 is pivotally connected at its other end by a link 79 to the upper end of the vertically movable piston rod 80 of the fluid pressure cylinder 81.

The lugs 71 on the carriages 67 are pivotally connected by the links 82 to the upper ends of the rocking levers 83, which are pivotally mounted at a point adjacent to their lower ends on the brackets 84. The levers 83 are pivotally connected at their lower ends, by links 85, to the lower end of the rocking levers 76, or end opposite that to which the links 75 are secured.

15 It will be apparent that when fluid pressure is admitted to the lower end of the cylinder 81 the piston rod 80 will move upwardly and cause the several levers to pull on and move the stops or fingers 42 and 43 toward and against the side edges of the plates to be matched.

20 The fingers 42 and 43 are arranged to be retracted or moved away from the edges of the matched plates by the springs 88 and 89, these springs having one end anchored to the shaft 77 and the other end thereof secured to the lower ends of the rocking levers 73 and 83 (see Figure 1).

25 The general operation of this doubling mechanism will be readily understood by those skilled in the art.

30 Attention is directed however, to the fact that the sheets are doubled by a downward movement thereof, between the rolls 7 and 7^a instead of moving upwardly. By doubling the sheets downwardly the operation is facilitated and the sheets are more closely doubled, since the packs of sheets have a curved formation as they come from the rolls, and when doubled upwardly this curve in the plates acts as a spring and prevents the plates being doubled closely together. It will also be noted that by doubling the sheets downwardly the major portion of the mechanism may be mounted in a pit below the floor level, thus saving valuable floor space in the mill.

35 While one specific embodiment of our invention has been illustrated and described it will be understood that various changes may be made in the design and structure and by the substitution of equivalents, without departing from the spirit of the invention as defined in the appended claims.

40 55 We claim:

1. A plate doubling mechanism comprising opposed rolls, means for driving said rolls, a doubling knife above said rolls, said knife being adapted to force plates into the bite of said rolls, means for operating said knife, and automatic means for reversing the direction of rotation of said rolls so as to feed said plates from between said rolls.

60 65 2. A plate doubling mechanism comprising

ing opposed plate doubling rolls, means for driving said rolls, a doubling knife above said rolls, said knife being arranged to force plates into the bite of said rolls, means for operating said knife, a tripping lever below said rolls in the path of plates passed therebetween, and means actuated by said lever for reversing the direction of rotation of said rolls so as to feed the plates in a reverse direction from between said rolls.

3. A plate doubling mechanism comprising a pair of rolls, means for rotating said rolls, means for matching a plurality of plates above said rolls, a doubling knife mounted for vertical movement above said rolls, means for moving said knife downwardly into position to force said plates into the bite of said rolls, and means operated by engagement by the plates in the passage thereof between said rolls for reversing the direction of rotation of said rolls, so as to feed said plates backwardly from between said rolls to the level at which the plates enter said rolls.

4. A plate doubling mechanism comprising a pair of rolls, means for positively rotating said rolls, a doubling knife above said rolls, said knife being adapted to force plates into the bite of said rolls, means for operating said knife, a tripping lever operated by engagement therewith of the plates in the passage thereof between said rolls, and means actuated by said lever for reversing the direction of rotation of said rolls, to thereby feed said plates backwardly from between said rolls to the entrance side thereof.

5. A plate doubling mechanism comprising a pair of spring pressed rolls, a motor and roll driving motor gearing operatively connecting said motor and rolls, a doubling knife mounted for vertical reciprocatory movement above said rolls, fluid pressure cylinders and levers connecting said cylinders with said knife for actuating said knife, said knife being adapted to move downwardly against said plates and thereby force said plates into the bite of said rolls, stops adapted to engage with the side and end edges of said plates in matching the plates, operating levers connecting said stops in pairs, fluid pressure cylinders for actuating said levers, and means operated by the plates in the passage thereof between said rolls for reversing the direction of rotation of said rolls to thereby feed said plates from between said rolls.

6. A plate doubling mechanism comprising a pair of spring pressed rolls, a roll driving motor and gearing operatively connecting said motor to said rolls, a doubling knife mounted for vertical reciprocatory movement above said rolls, fluid pressure cylinders and levers connecting said cylinders with said knife for reciprocating

said knife, said knife being adapted to move downwardly against said plates to move the plates into the bite of said rolls, stops adapted to engage the side and end edges 5 of said plates to match the same, a tripping lever below said rolls adapted to be actuated by engagement of the plates therewith in the passage of the plates between said rolls, and means actuated by said tripping

lever for reversing said motor to change 10 the direction of rotation of said rolls and thereby feed said plates from between said rolls to the entrance side of said rolls.

In testimony whereof we have hereunto set our hands.

STORM B. HAARBYE.
HOWARD G. McILVRIED.
